(57) **CLAIM**

The ornamental design for a cutting insert for chip removal, as shown and described.

DESCRIPTION

FIG. 1 is a top view of the cutting insert for chip removal; FIG. 2 is a side view of the cutting insert for chip removal; FIG. 3 is a bottom view of the cutting insert for chip removal;

FIG. 4 is a perspective view of the cutting insert for chip removal; and,

FIG. 5 is an end view of the cutting insert for chip removal. The broken lines show the environment with which the design is associated, are for illustrative purposes only, and form no part of the claimed design or a specified embodiment thereof.
